DESIGN FOR A CASH REGISTER

Max Garbell, Chicago, Ill., assignor to Victor
Adding Machine Company, Chicago, Ill., a corporation of Delaware

Application December 28, 1935, Serial No. 60,324

Term of patent 14 years

To all whom it may concern:

Be it known that I, Max Garbell, a citizen of the United States of America and a resident of Chicago, Cook County, Illinois, have invented a new, original, and ornamental Design for a Cash Register, of which the following is a specification, reference being had to the accompanying drawing, forming a part thereof.

I claim:

The ornamental design for a cash register substantially as shown.

MAX GARBELL.
